UNITED STATES PATENT OFFICE.

JAMES K. DALTON, OF WAVERLY, OHIO.

SAFETY-ENVELOP.

1,148,220.

specification of Letters Patent. Patented July 27, 1915.

Application filed December 26, 1914. Serial No. 879,172.

To all whom it may concern:

Be it known that I, JAMES K. DALTON, a citizen of the United States, residing at Waverly, in the county of Pike and State of Ohio, have invented certain new and useful Improvements in Safety-Envelops; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in safety envelopes and the object in view is to produce a simple and efficient device of this nature so constructed that it will be impossible to open the same without detection.

More specifically, the invention consists of an envelop in the back of which a groove is formed and adapted to contain an indelible chemical or analogous material which will, if subjected to steam or water, cause the same to flow and disclose that the envelop has been tampered with.

The invention comprises various details of construction, combinations and arrangements of parts which will be hereinafter fully described, shown in the accompanying drawings and then specifically defined in the appended claim.

I illustrate my invention in the accompanying drawings, in which:

Figure 1 is a rear elevation of an envelop made in accordance with my invention, and Fig. 2 is a cross sectional view.

Reference now being had to the details of the drawings by letter, A designates an envelop of any shape or size and B is a groove

formed in the back thereof, preferably near the upper marginal edge and over which the flap C is adapted to be folded. Said groove, which in the present instance is angular at its center, has a filler E therein of indelible material and a covering D is fastened over the grooved face holding the filler in place, and forming means whereby the indelible material will not be accidentally spread in the event of a person moistening the envelop to cause the adhesive material upon the flap to adhere to the envelop.

In the event of an attempt being made to open the envelop by subjecting the adhesive material upon the flap to steam or water for the purpose of loosening the sealing material, the moisture or steam will so act upon the indelible material that it will flow from the groove and spread, thus showing that the envelop has been tampered with, it being understood that the strip of material D is of such a nature that moisture will readily pass through the same when the envelop is subjected to water or steam.

What I claim to be new is:

A safety envelop having a groove, longitudinally angled, impressed in the rear thereof, the ends of the groove terminating slight distances from the ends of the upper edges of the back adjacent to the ends, a filler within said groove and flush with the rear face of the envelop, a sealing flap of the envelop adapted to fold over and close said groove its entire length and seal to the back.

In testimony whereof I hereunto affix my signature in presence of two witnesses.

JAMES K. DALTON.
